(57) **CLAIM**

The ornamental design for a display panel or portion thereof with graphical user interface, as shown and described.

DESCRIPTION

FIG. 1 is a front view of a display panel or portion thereof with graphical user interface showing a first embodiment of our design;

FIG. 2 is a front view of a display panel or portion thereof with graphical user interface showing a second embodiment thereof;

FIG. 3 is a front view of a display panel or portion thereof with graphical user interface showing a third embodiment thereof; and,

FIG. 4 is a front view of a display panel or portion thereof with graphical user interface showing a fourth embodiment thereof.

The outermost broken line rectangle illustrates a display panel or portion thereof and forms no part of the claimed design. The remaining broken lines illustrate portions of a graphical user interface or a mixed reality environment and form no part of the claimed design.

1 Claim, 4 Drawing Sheets
